UNITED STATES PATENT OFFICE.

JOHN WILLIAM SAGER, OF CHICAGO, ILLINOIS, ASSIGNOR TO WESTERN ELECTRIC COMPANY, INCORPORATED, OF NEW YORK, N. Y., A CORPORATION OF NEW YORK.

WINDING MECHANISM.

Application filed March 30, 1925. Serial No. 19,461.

This invention relates to improvements in winding mechanisms, and more particularly to a high speed coil winding mechanism. The object of this invention is to provide in a winding machine an improved means to rapidly and accurately distribute material in smooth even layers on a core.

Other advantages and features will become apparent from the following detailed description taken in connection with the accompanying drawings, in which—

Fig. 1 is an enlarged side elevation of a coil winding machine embodying the invention;

Figs. 2 and 3 are plan and end views respectively thereof;

Fig. 4 is an enlarged plan view, partly in section, of the counting mechanism;

Fig. 5 is a section taken on the line 5—5 of Fig. 2 and looking in the direction of the arrows;

Fig. 6 is a side view of the reversing mechanism;

Fig. 7 is an enlarged section taken on the line 7—7 of Fig. 2 and looking in the direction of the arrows, and

Figs. 8, 9 and 10 are detail views taken on the lines 8—8, 9—9 and 10—10 respectively of Fig. 5.

In the drawings in which like reference characters designate like parts throughout the several views, 15 denotes a base, and 16 a housing mounted thereon. Also mounted on the base 15 is a vertical plate 17. A main drive shaft 18 is suitably mounted in bearings in the ends 19 and 20 of the housing 16, and has a worm 21 formed thereon. Keyed to one end of the shaft are a hand wheel 22 and a grooved pulley 23, the other end of the shaft 18 being provided with a chuck 24 which serves to hold a core 25 on which wire or other strand material is to be wound. The shaft 18 is driven through the pulley 23 and a belt 26 which may be driven by any suitable source of power (not shown).

A counting mechanism indicated generally by the numeral 30 and shown in detail in Figs. 4 and 5 includes a shaft 31 rotatably mounted in a support 32. Keyed to one end of the shaft 31 is a knob 33 and also keyed to the same shaft is a sleeve 35 and slidably mounted thereon by a pin 36 and slot 37 is a finger 34. A sleeve 38 is loosely mounted on the shaft 31 and a number wheel 40,

to which a gear 39 is secured by screws 41, is keyed thereto. A sleeve 42 is also loosely mounted on the shaft 31 and has a number wheel 43 keyed thereto. An annular groove 44 is provided in the wheel 40 (Fig. 8), and a pin 45 is mounted in the groove at a point corresponding to the zero marking on the wheel. A hole 46 is located in the wheel 43 in line with the groove 44 in the wheel 40 and at a point corresponding to the zero marking on the wheel 43. A member 47 is keyed to a reduced portion of the shaft 31 and carries a pin 49, one end of which extends through the hole 46 in the wheel 43, and the other end thereof engages one of a plurality of holes 50 in a hubbed disk 51. The number of the holes 50 preferably corresponds with the number of markings appearing on the periphery of the wheel 43. The number wheel 43 is held in close proximity with the number wheel 40 by springs 52 which also serve to hold the member 47 in position to retain the pin 49 in the hole 50. A shaft 55, in alignment with the shaft 31, is suitably mounted in the housing 16 and plate 17. Keyed to one end of the shaft 55 and located in the housing 16 is a worm gear 56 which is driven by the worm 21. The hubbed disk 51 is secured to the worm gear 56 by screws 57. Keyed to a reduced portion at the other end of the shaft 55 is a flanged sleeve 58 which carries a pair of pawls 59 adapted to engage a ratchet wheel 60 which is rotatably mounted on the sleeve 58 and keyed to a pinion gear 61 also rotatably mounted on the sleeve. The pinion gear 61 and ratchet 60 are held in place by nuts 62. When the machine is in operation the worm 21 drives the worm gear 56 which drives the shaft 55 to which the sleeve 58 is keyed and the pawls 59 engage the ratchet 60 and turn the pinion gear 61, thus driving a reversing mechanism hereinafter described.

Mounted in the support 32 is an apparatus for controlling and driving the number wheel 40 comprising a member 65, one end 66 of which is flanged and the other end of which has fastened thereto a wheel 67 having teeth 68 engageable by the finger 34. The inner side of the flanged end 66 has a plurality of depressions 69 any of which may be engaged by a spring pressed plunger 70. A shaft 71 carries a pinion gear 72 which meshes with the gear 39.

As the machine operates the worm 21 through engagement with the worm gear 56 drives the counting mechanism 30. The hubbed disk 51 is driven by the worm gear 56 and the member 47 is driven by the disk 51 since the attached pin 49 engages one of the holes 50 in the disk. The pin 49 also engages the hole 46 in the number wheel 43, turning the wheel therewith. The ratio between the worm 21 and the worm gear 56 is one hundred to one, the number wheel 43 making one complete revolution for each hundred revolutions of the shaft 18. The number wheel 43 is used to indicate the turns in units and tens and has a double column of figures on its periphery extending from 0 to 99. Since each time the shaft 18 completes one revolution, one turn of wire is wound on the core 25, the number wheel 43 is advanced one one-hundredth of a revolution advancing the numbers marked on its periphery one unit.

The finger 34 rotates with the member 47. When one hundred turns of wire have been wound on the core 25 the wheel 43 will have advanced one complete revolution, and the finger 34 engages one of the teeth 68 of and thereby rotating the wheel 67 and the member 65 to which the wheel is keyed a sufficient angular distance to cause the spring pressed plunger 70 to engage the next depression 69 and for the gear 72 to move the gear 39 and the attached wheel 40 one one-hundredth of a revolution. The periphery of the wheel 40 is marked in the same manner as that of the wheel 43 to indicate the turns in hundreds and thousands. The wheel 40 makes one complete revolution for each one hundred revolutions of the wheel 43 or in other words one hundred turns of wire on the core 25 are required to advance the wheel 40 one unit and ten thousand turns to advance the wheel 40 one complete revolution. The number of turns of wire which have been wound on the core 25 will be constantly indicated by the numbers on the wheels as just described. It is obvious that the counter mechanism is geared for an extremely high speed winding machine and since only two number wheels are employed as well as due to the simple construction used the parts receive a minimum of wear in proportion to the amount of winding done.

The counting mechanism 30 may readily be changed to a starting position at any time by pulling the knob 33 outwardly. The shaft 31 slides through the sleeves 42 and 38 and draws the member 47 into close proximity with the number wheel 43 thereby compressing the springs 52 as well as disengaging the pin 49 from the hole 50 in the disk 51, and extending the opposite end of the pin through the hole 46 in the wheel 43 into the annular groove 44 in the wheel 40. The sleeve 35 on which the finger 34 is

mounted also slides with the shaft 31 so that the finger 34 cannot engage the teeth 68 of the wheel 67 leaving it free to rotate. The knob 33 may be turned in either direction, rotating the wheel 43 therewith. The pin 49 riding in the annular groove 44 of the wheel 40 engages the pin 45 mounted in the groove and thereby turns the wheel 40. As hereinbefore described the pin 45 is mounted in the groove 44 at a point corresponding to the zero marking on the wheel 40 and the hole 46 in the wheel 43 is located at a point corresponding to the zero marking on its periphery. It is obvious that in the resetting operation the zero figures on both wheels correspond when the pin 49 engages the pin 45.

A pair of levers 121 and 122 secured together and rotatably mounted at their lower ends upon the base 15 are in association with the mechanism just described. A tension spring 123 serves to hold the upper end of the lever 122 in close relation with a member 124 having a slot 125 in its side engaged by the upper end of the lever 121. The member 124 has an inwardly projecting end 126 which engages an annular groove 127 in the knob 33. When the knob 33 is pulled outwardly the member 124 is drawn inwardly by the engagement of its end 126 and the groove 127. The upper end of the lever 122 is forced into the slot 125 through tension induced by the spring 123 which movement causes the lever 121 to fall in the path of a pin 130 mounted on the outer surface of the gear 39. The top of the lever 121 acts as a stop by engaging the pin 130 when the gear has been turned back far enough for the number wheels to be in position to start a new count.

A distributing means designated generally by the numeral 76 distributes the wire evenly on the core 25 and comprises an adjusting screw 80 which carries a guide roller 27 and is supported in a distributing arm 79 slidably mounted on a rod 77, one end of which is mounted in the housing 16 and the other end in an arm 78 secured to the plate 17. An extended arm 81 secured to the distributing arm 79 forms a rack segment 82 which engages a rack 83 supported in a bracket 84 and in the end of the arm 78 causing the distributing means 76 to move with the rack 83.

A gear reversing mechanism indicated generally by the numeral 75 (Figs. 2, 3, 6 and 7) is provided for driving and controlling the distributor means 76. A shaft 85 is suitably mounted in a bracket 86 and in the housing 16. Rotatably mounted on the shaft 85 is a sleeve 87 on which is formed a gear 99 engaging the rack 83. Keyed to the sleeve 87 are two levers 88 and 89 in the ends of which is rotatably mounted a shaft 90. Rotatably mounted on the sleeve 87 is

a hub 91 having two gears 92 and 93 keyed thereto. A similar hub 94 is rotatably mounted on the sleeve 87 and two gears 95 and 96 are keyed thereto. The gear 61 drives a gear 97 suitably mounted on the gages the other surface of the cam 110, the plate 17 and a gear 98 formed integral with the spring 118 returns the member 111 downwardly when the roller end 109 over the apex of the cam 110 compresses the spring 118 and forcing the member 111 downwardly when the roller end 109 shifts the double pawl 105 to disengage the end 107 from the gear 95 and engage the end 106 with the gear 93 which is rotating in an opposite direction to that of gear 95. It is obvious that the direction in which the levers 88 and 89 are moving will change when the operation just described takes place and they will continue in the opposite direction until the shaft 85 has rotated far enough for the lever 140 to engage the other stop 142 which will cause the roller 109 again to cross the apex of the cam arm 110 and shift the double pawl 105 to release the engaged end 106 and engage the end 107, thus again reversing the direction of travel as described. In this manner the levers 88 and 89 are caused to reciprocate at predetermined intervals oscillating the sleeve 87 keyed thereto, and the gear 99 which engages the rack 83 and imparts the reciprocating motion thereto. The distributing finger 79 is connected to the rack 83 as hereinbefore described and moves with the rack as the machine operates evenly distributing the wire being wound on the core 25.

The shaft 90 has a double pawl member 105 keyed thereto, a pawl 106 on one end of which is adapted to engage the gear 93 and a pawl 107 on the other end is adapted to engage the gear 95. A member 108 is keyed to the shaft 90 and carries a roller 109 which is engaged by an angular cam surface 110 of a member 111. The member 111 is slidably mounted on a sleeve 112 which is keyed to the shaft 85. Keyed to the opposite end of the shaft 85 is an arm 140 adapted to reciprocate between two stops 141 and 142 which are adjustably mounted in an arcuate slot 143 in a plate 144. A slot 114 permits a vertical movement of the member 111 which is limited by a stop 115 formed on the support 89 and extending through a slot 116 in the member 111. A pair of pins 117 serve as guides for the movement of the member 111. A compression spring 118 resists the downward motion of the member 111 which member is guided by a pin 119 slidable in an elongated portion 120 of the sleeve 112. What is claimed is:

1. In a material distributing mechanism, a rack, a material distributing member secured thereto, a pair of gears, means to rotate the gears in opposite directions, and means including a resiliently mounted cam having an upwardly disposed surfaces engaging a roller carried by a ratchet mechanism operating at predetermined intervals to operatively associate the gears alternately with the rack to cause the member to distribute the material in opposite directions.
2. In a material distributing mechanism, a rack, a distributing member secured thereto, a pair of gears, means to rotate the gears in opposite directions, a shaft, a gear carried thereby and engaging the rack, means operating at predetermined intervals to operatively associate the gears alternately with the shaft to cause the member to distribute material.

the material in opposite directions, and adjustable means including an arm carried by the shaft and a pair of adjustable spaced stop members engaged thereby for changing the 5 lengths of the intervals.

3. In a material distributing mechanism, a material distributing means, a pair of gears, means to rotate the gears in opposite directions, and means including a cam and a 10 double pawl ratchet mechanism carrying a roller engaging the cam and operating at predetermined intervals for operatively associating the gears alternately with and thereby moving the distributing means in 15 opposite directions.

4. In a material distributing mechanism, a material distributing means, a pair of gears, means to rotate the gears in opposite directions, a ratchet mechanism including a 20 ratchet wheel carried by each of the gears and a ratchet member common thereto, a roller, and a resiliently mounted cam member engaged thereby to actuate the ratchet member at predetermined intervals for operatively associating the gears alternately with and thereby moving the distributing means in 25 opposite directions.

5. In a material distributing mechanism, a rack, a material distributing means carried 30 thereby, a gear meshing with the rack, a driving gear, and a ratchet mechanism including a ratchet wheel mounted on the driving gear and operated thereby and actuating the first mentioned gear to move the rack to 35 thereby distribute the material.

6. In a material distributing mechanism, a rack, a material distributing means carried thereby, a shaft, a gear rotatably mounted thereon and meshing with the rack, a driven 40 gear, a ratchet mechanism including a pawl and a ratchet wheel carried by the driven gear and actuating the first mentioned gear to move the rack and thereby distribute the material, a roller carried by the pawl, a 45 resiliently mounted cam member secured to the shaft and engaged by the roller to cause a rotation of the shaft, and means including an arm carried by the shaft and a stop member engaged thereby to stop the rotation of 50 the shaft and thereby cause the cam member and roller to disengage the pawl from the ratchet wheel.

7. In a material distributing mechanism, a rack, a material distributing means carried 55 thereby, a shaft, a gear rotatably mounted

thereon and meshing with the rack, a pair of oppositely rotating gears also rotatably carried by the shaft, a ratchet wheel carried by each of the oppositely rotating gears, a ratchet member having pawls for engaging 60 each of the wheels, a resiliently mounted plural surfaced cam secured to the shaft, a roller carried by the member and engaging one of the surfaces of the cam to drive the shaft and the first mentioned gear in the 65 same direction as the ratchet wheel engaged by one of the pawls, thereby moving the rack and distributing means in one direction, means for stopping the rotation of the shaft to cause a relative movement between the 70 cam member and the roller for transferring the roller to another surface of the cam and simultaneously therewith to disengage the engaged pawl and engage the other pawl with the other ratchet wheel to rotate the 75 shaft and the first mentioned gear in an opposite direction, thereby reversing the direction of the rack and the distributing means.

8. In a material distributing mechanism, a rack, a material distributing means carried 80 thereby, a shaft, a gear rotatably mounted thereon and meshing with the rack, a pair of oppositely rotating gears also rotatably carried by the shaft, a ratchet wheel carried by each of the oppositely rotating gears, a 85 ratchet member having pawls for engaging each of the wheels, a resiliently mounted plural surface cam secured to the shaft, a roller carried by the member and engaging one of the surfaces of the cam to drive the 90 shaft and the first mentioned gear in the same direction as the ratchet wheel engaged by one of the pawls, thereby moving the rack and distributing means in one direction, an arm carried by the shaft and adjustable 95 means to be engaged by the arm for stopping the rotation of the shaft to cause a relative movement between the cam member and the roller for transferring the roller to another surface of the cam and simultaneously therewith to disengage the engaged pawl and engage the other pawl with the other ratchet wheel to rotate the shaft and the first mentioned gear in an opposite direction, thereby 100 reversing the direction of the rack and the distributing means.

In witness whereof, I hereunto subscribe my name this 21 day of March A. D., 1925.

JOHN WILLIAM SAGER.
